MULTIPLE BOLT RIM NIGHT LATCH

Henry G. Voight, Hamden, Conn., assignor to
Sargent & Company, New Haven, Conn., a corporation of Connecticut

Application December 4, 1943, Serial No. 512,848

10 Claims. (Cl. 292—5)

This invention relates to locks, and while applicable to other kinds of locks, it is illustrated as applied to a night latch which is adapted to be operated from one side by a thumb turn and from the other side by a key. Also as illustrated, the improvements are applied to what is termed a rim lock in that, as shown, the lock case is mounted upon the exterior surface of the door instead of being mortised in the door, as is frequently the custom.

In locks or latches of this character the mechanism is usually provided with a bolt which may be either a dead bolt or latch bolt adapted to be protracted from the case into engagement with a strike. Some difficulty has been encountered with such constructions in the past in that they have been subject to being "jimmied" or being forced open by a tool inserted between the bolt and strike, and thus forcing the bolt rearwardly into the case.

It is contemplated by the present invention to provide a lock which shall be jimmy proof, in that the bolt operates in such a manner that it cannot be retracted or disengaged from the strike by a tool inserted between the bolt and strike at the outside of the door. In accomplishing this function the lock is so constructed that the bolt member, which is protracted into engagement with the strike, is not only moved longitudinally but also swung about a pivot on a bolt carrier so that it cannot be retracted by a longitudinal movement alone, but there must also be imparted to it a reverse swinging movement to free it from the strike. Moreover, in the present instance a plurality of such swinging bolt members are provided, thus rendering it increasingly difficult to "jimmie" the lock and thus effect entrance to the door.

One object of the present invention is to provide a door lock which shall be substantially jimmy proof.

A further object of the invention is to provide a lock of the so-called night latch type, in which the bolt when projected from the lock case will be given a swinging movement to embrace, or partially embrace, a strike member whereby it must, upon retraction, undergo a swinging movement in a reverse direction.

A still further object of the invention is to provide a rim lock of the character described which shall be simple in construction and operation, and at the same time be proof against being opened by a tool inserted between the lock case and the strike.

To these and other ends the invention consists

in the novel features and combinations of parts to be hereinafter described and claimed.

In the accompanying drawing:

Fig. 1 is a sectional view of a lock embodying my improvements, showing the lock as applied to the surface of a door;

Fig. 2 is a sectional view of the lock on line 2—2 of Fig. 1, showing the parts as they appear with the cover of the lock case removed and the bolts in protracted position;

Fig. 3 is a sectional view on line 3—3 of Fig. 2, and

Fig. 4 is a fragmentary horizontal sectional view similar to Fig. 1 but showing the front portion of the lock only, and showing the bolts in retracted position.

In illustrating a preferred embodiment of my invention I have shown a door 10 having mounted on the inner surface thereof a lock case 11 provided with a cover 12, the cover being secured in place by means of a post 13 secured to the case 11 and receiving a suitable fastening member such as a screw entering through an opening in the cover 12. The case is provided in its forward end with a plurality of spaced bolt openings 11a.

Cooperating with the lock case is a strike 14 adapted to be mounted on the door frame. As shown, a strike member 15 is carried by the strike, this member being in the form of a vertically disposed bar or rod of circular cross section secured to the member 14 adjacent the front wall thereof. The strike 14, as is usual, is open on the side toward the lock case 11, so as to receive the bolt or bolts of the lock upon protraction thereof.

Mounted in the lock case is a bolt carrier 16 having at its lower corner a rearwardly extending tail portion 17 which is rigid with the carrier and may be formed integrally therewith. Upon the tail portion 17 is pivoted at 18 a tumbler 19, the tumbler being urged in a counterclockwise direction about its pivot by means of a spring 20, one end of which is engaged with the tumbler and the other end lodged against a lug 21 on the portion 17 of the carrier.

The end 22 of this tumbler projects upwardly between talons 23 formed at the rear end of the tail portion 17 of the bolt carrier, which tail portion is also provided with a longitudinally extending slot 24 in which is slidably received a post 25 secured to the lock case 11. The tumbler 19 is provided with a detent 26 normally engaged with the post 25, but which may be disengaged from the post by rotation of the tumbler in a clockwise direction against the action of the spring 20.

The bolt carrier 16 is provided with a plurality of recesses or slots 28, three in number, as shown. In each of these slots is mounted a bolt 29, each of these bolts being pivoted to a pin 30 secured to the carrier, and the slots 28 are, as shown in Fig. 1, of sufficient extent laterally so as to permit swinging movements of the bolts about the pivot pin.

As shown more particularly in Figs. 1 and 4, the forward end of each of the bolts is hook-shaped in form, as at 31, the inner surface of the end being rounded as shown at 32, so that the bolt when protracted may partially embrace the strike member 15. The cooperating surfaces of the strike member 15 and the portion 32 of each of the bolts are such that when each of the bolts is retracted it will, if permitted a swinging movement, be cammed by these cooperating surfaces to swing about its pivot so that it will pass out of engagement with the strike member.

It will also be noted that each of the bolts is provided with a tail portion 33 on the opposite side of its pivot from its forward end 31, with which tail portion is adapted to cooperate a rib 34 formed on the case and of a sufficient length in a vertical direction to engage the tail pieces of all of the bolts. Thus it will be apparent that, as the bolt carrier is moved forwardly from the position shown in Fig. 4 to that shown in Fig. 1, the bolts 29 will be protracted from the case, and that as they approach their extreme protracted positions the tail portions 33 will strike the rib 34, and the bolts will be swung about their pivots 30 to hook over or embrace the strike rod 15, thus securely locking the door in closed position. When the bolt carrier is moved rearwardly from the position shown in Fig. 1, the tail portions 33 of the bolts will be moved away from the rib 34 and thus will permit the bolts to be cammed by the strike member 15 in a reverse direction, thus disengaging this strike member and permitting the bolts to be retracted into the lock case, as shown in Fig. 4.

The bolt carrier may be operated by any desired means. As shown, however, a rollback 36 is secured to a hub 37 rotatably mounted in the case, to which hub is secured a thumb turn 38 at the outside of the case but on the inside of the door, so that the rollback 36 may be freely rotated by the thumb turn. The rollback is provided with a pair of posts 39, one upon each end, designed to enter between the talons 23, and by engaging the end 22 of the tumbler 19 free the detent 26 from engagement with the post 25. After this has been done continued rotation of the rollback will cause one of the posts 39 to engage one of the talons 23 and move the bolt carrier 16 in the desired direction, the carrier, of course, bringing the bolts with it.

To maintain the rollback 36 in a neutral position, as shown in Fig. 2, a bar 40 is pivoted to the case at 41, and maintained by a spring 42 in a position in which its lower surface bears against the posts 39. When the rollback is actuated the bar 40 will, of course, be moved upwardly about its pivot against the tension of its spring, but will be returned by the spring to the position shown in Fig. 2 to normally hold the rollback in its neutral position.

At the outside of the door there may be provided a key-operated lock 44 having a stem 45 in non-rotative engagement with the hub 37 so that this hub and the rollback 36 may be actuated from the outside of the door by a key. It is not deemed necessary to show the details of this key-

operated lock structure, as they may be of the usual form well known in the art.

It will be seen that when the bolts 29 are protracted as shown in Figs. 1 and 2, they cannot be forced rearwardly by a tool inserted between the lock case and the strike as they must be swung about their pivots before this movement can be effected, and any such swinging movement is prevented by the engagement of the tails 33 of the bolts with the rib 34, so that the lock may not be "jimmied" in this manner. When it is desired to open the door, however, the rollback 36 may be actuated either from inside or outside of the door, this rollback serving first to disengage the tumbler 19 from the detent 25, and thereafter to engage one of the talons 23 and move the bolt carrier and bolts rearwardly, the bolts being disengaged at this time from the strike member 15.

While I have shown and described a preferred embodiment of my invention, it will be understood that it is not to be limited to all of the details shown, but is capable of modification and variation within the spirit of the invention and within the scope of the claims.

What I claim is:

1. In a door lock, a case having a bolt opening, a bolt carrier slidably mounted in the case, a bolt pivotally carried by said carrier to swing about a vertical axis, means to reciprocate said carrier to retract said bolt into the case and protract it therefrom through said opening, and means in fixed position on the case to engage said bolt during the protraction thereof and effect a swinging movement of the bolt about its axis, said bolt being pivoted adjacent its rear end to the carrier and extending forwardly from the front edge thereof to project from the case while the carrier is retained therein.

2. In a door lock, a case having a bolt opening, a bolt carrier slidably mounted in the case, a bolt pivotally carried by said carrier to swing about a vertical axis, means to reciprocate said carrier to retract said bolt into the case and protract it therefrom through said opening, means in fixed position on the case to engage said bolt during the protraction thereof and effect a swinging movement of the bolt about its axis, and a strike member comprising a vertically disposed bar which said bolt embraces when protracted and swung about its pivot, said bolt being pivoted adjacent its rear end to the carrier and extending forwardly from the front edge thereof to project from the case and engage the strike member while the carrier is retained within the case.

3. A lock as in claim 1, wherein the bolt carrier comprises a relatively wide member extending vertically of the case and carries a plurality of said pivoted bolts spaced along its width.

4. A lock as in claim 1, wherein the bolt carrier comprises a relatively wide member extending vertically of the case and carries a plurality of said pivoted bolts spaced along its width, in combination with a strike member comprising a vertically disposed bar embraced by said bolts when protracted.

5. In a night latch, a case, a bolt carrier slidably mounted in the case, a plurality of bolts pivotally carried by the carrier and arranged in spaced relation, said case being provided with openings to permit protraction of said bolts when said carrier is moved toward the front of the case, each of said bolts being provided with a tail portion, and means on the case to engage the tail portion of each of the bolts and swing the latter

about their pivots when the carrier nears the end of its forward movement.

6. In a night latch, a case, a bolt carrier slidably mounted in the case, a plurality of bolts pivotally carried by the carrier and arranged in spaced relation, said case being provided with openings to permit protraction of said bolts when said carrier is moved toward the front of the case, each of said bolts being provided with a tail portion, means on the case to engage the tail portion of each of the bolts and swing the latter about their pivots when the carrier nears the end of its forward movement, and a strike member carrying a vertically disposed bar to be embraced by said bolts when protracted.

7. In a night latch, a case, a bolt carrier slidably mounted in the case, a plurality of bolts pivotally carried by the carrier and arranged in spaced relation, said case being provided with openings to permit protraction of said bolts when said carrier is moved toward the front of the case, each of said bolts being provided with a tail portion, means on the case to engage the tail portion of each of the bolts and swing the latter about their pivots when the carrier nears the end of its forward movement, a strike member carrying a vertically disposed bar to be embraced by said bolts when protracted, and means to effect reverse movement of said bolts about their pivots when the carrier is moved rearwardly to retract the bolts.

8. In a night latch, a case, a bolt carrier slidably mounted in the case, a plurality of bolts pivotally carried by the carrier and arranged in spaced relation, said case being provided with openings to permit protraction of said bolts when said carrier is moved toward the front of the case, each of said bolts being provided with a tail por-

tion, and means on the case to engage the tail portion of each of the bolts and swing the latter about their pivots when the carrier nears the end of its forward movement, said bolts having hook-shaped ends to engage a strike member.

5 9. In a night latch, a case, a bolt carrier slidably mounted in the case, a plurality of bolts pivotally carried by the carrier and arranged in spaced relation, said case being provided with openings to permit protraction of said bolts when 10 said carrier is moved toward the front of the case, each of said bolts being provided with a tail portion, and means on the case to engage the tail portion of each of the bolts and swing the latter about their pivots when the carrier nears the end of its forward movement, said means comprising a rib extending vertically along a wall of the case adjacent the front portion thereof.

15 10. In a night latch, a case, a bolt carrier slidably mounted in the case, a plurality of bolts pivotally carried by the carrier and arranged in spaced relation, said case being provided with openings to permit protraction of said bolts when 20 said carrier is moved toward the front of the case,

25 25. means on the case to engage the tail portion of each of the bolts and swing the latter about their pivots when the carrier nears the end of its forward movement, and a strike member carrying a vertically disposed bar to be embraced by said bolts when protracted, said bolts having hook-shaped ends to embrace said bar when 30 swung about their pivots by engagement of the tail portions thereof with said means, and being 35 reversely moved about their pivots by engagement with said bar upon retraction of the bolts when the tail portions are disengaged from said means.

HENRY G. VOIGHT.
